GRINDING MACHINE

Charles H. Norton, Plainville, Conn., and Albert G. Belden, Worcester, Mass., assignors to Norton Company, Worcester, Mass., a corporation of Massachusetts

Application October 3, 1931, Serial No. 566,738
Renewed February 24, 1936

24 Claims. (Cl. 51—103)

This invention relates to grinding machines and particularly to a machine adapted for grinding round work to a predetermined size.

Owing to keen competition and the present day demands for rapid production of duplicate, accurately shaped, cylindrical work pieces, a large percentage of the machining of such work involves the use of automatic machinery which must be capable of rapidly finishing successive work pieces within exceedingly narrow limits of accuracy and producing exactly the required finish upon each piece of work. Many of the work pieces subjected to a precision grinding operation, such as roller bearings and the like, comprise short cylindrical pieces which require being ground throughout their entire length by a wide wheel. To support and rotate work pieces of this type for a precision grinding operation has heretofore presented various problems which have been met largely by two types of grinding machines. One type involves what is commonly known as the centerless principle, wherein the work piece is ground between a rapidly rotating grinding wheel and a slowly rotating speed regulating wheel, the work being supported upon a fixed support between the two wheels. However, a centerless machine of this type has been found unsuitable for continuously grinding within the narrow limits of accuracy necessary for various types of work, and particularly work which must have its cylindrical surface concentric with its axis. A further inherent difficulty in such a machine is its tendency to produce chatter marks upon the work surface owing to vibration within the machine and the non-uniform rotation of the work piece between the two abrasive wheels. Also, it has been found impracticable to remove a large amount of stock with a single pass of the work through the machine.

It has further been contemplated to perform a grinding operation by the so-called one wheel centerless method wherein the work is peripherally supported in a dovetailed channel of a guide bar while it is simultaneously rotated, moved axially and ground by means of a grinding wheel. In many instances, this type of grinding has proved unsatisfactory, due to the fact that the rotative action of the rapidly rotated wheel against the work periphery produced an uneven work rotation which resulted in producing flat portions or other defects on the work surface. In such a grinding operation, the work is not rotated positively and uniformly and it is not supported properly; hence there is a tendency

for inaccuracies in the work contour to be produced and amplified during grinding.

Another machine which has been utilized to grind this type of work is of the type shown in the prior patent of Norton, No. 1,779,779, wherein the work is mounted on centering hubs and positively rotated by an end pressure gripping mechanism while the grinding wheel is fed through a predetermined cyclic movement to grind the work to required size.

It has been found that if a work piece of an irregular shape is peripherally supported by a work steadyng shoe having a concave surface of a radius of curvature equal to that of the desired finished work piece and if the work axis is permitted to move freely while the work is being positively rotated within the shoe, the grinding operation will proceed through a progressive series of approximations until the work is reduced to a cylindrical surface which mates with the curved surface of the work supporting shoe and has a radius of curvature equal to that of the shoe. During this operation, the grinding wheel and work will, of course, be fed relatively towards each other to produce the necessary removal of stock from the work piece.

It is therefore, one object of this invention to utilize this theory of grinding and to provide a grinding machine operated either manually or automatically, which is especially adapted for grinding a work piece rapidly and accurately to a required cylindrical surface.

A further object of this invention is to provide a precision grinding machine of this type wherein the work is positively ground by means of a grinding wheel fed relatively towards the work to a predetermined position to produce a desired cylindrical work size, and wherein the work is peripherally supported substantially throughout its entire length against the thrust of the grinding wheel and rotated by positively acting work rotating mechanism which does not serve to support the work.

It is a further object to provide a grinding machine of this type wherein successive work pieces may be mechanically fed to and from the work supporting member in correct timed relation to the grinding cycle and with a minimum loss of time. Further objects will be apparent in the following disclosure.

In accordance with our invention, we propose to support a rotating work piece against the grinding wheel thrust by means of a work supporting and steadyng member engaging the peripheral surface of the work and to feed the grinding

wheel and the rotating work relatively towards each other to grind the peripheral surface to a desired size. This steadyng member preferably comprises one or more shoes having a partial 5 cylindrical surface, or elements thereof, which has the radius of the finished work piece and so fits or mates with the peripheral work surface when the latter has been ground to its correct final size, thereby aiding in perfecting the work 10 surface. The rate of the work rotation is governed by a positively driven device which is independent of the work supporting and grinding members. This device preferably comprises members gripping 15 against the ends of the work piece or non-supportably engaging the same at points remote from the surface being ground. The wheel and the work are preferably rotated in the same direction at the point of tangency and the parts are so coordinated and arranged that any 20 rotative impulse imparted by the wheel to the work is utilized and controlled, whereby the driving mechanism may serve with small effort to insure a positive and controlled work rotation. In a machine embodying these features, provision is made 25 whereby, as the work decreases in size and its axis moves radially in the support, the positively driven rotating members which govern the work rotation will maintain efficient driving contact with the work without being required to support 30 it and maintain its axis in a given position. For this purpose we may employ a universal driving connection engaging the work at a position remote from the surface being ground, although various other means for rotating the work positively may 35 be employed.

As hereinafter explained, these various features which are applicable to a simple manually operated machine may also be embodied in a machine operated automatically, wholly or in 40 part, for grinding a plurality of work pieces to duplicate size and shape. In the embodiment of our machine as illustrated, the work steadyng member is adapted to receive the work from a suitable supply and to have the work automatically 45 removed therefrom upon completion of the grinding cycle. The machine illustrated utilizes a hopper or other feeding device arranged to present work pieces successively to the work steadyng and supporting member, and this may be 50 easily accomplished by so locating the various machine parts that the work steadyng member may be moved away from the grinding wheel to receive a work piece from the feeding device and then moved toward the grinding wheel to present 55 the work piece in the grinding zone. The finished work pieces may be removed either manually or automatically from the work supporting member just prior to its receiving a fresh work blank for presentation to the grinding wheel.

60 This invention has been illustrated as applied to a grinding machine embodying various automatic features set forth in the prior patent to Charles H. Norton, No. 1,779,779 wherein the grinding wheel is automatically fed into the work 65 by a cam controlled cross feed mechanism and the work rotation is effected by a mechanism operating in timed relation therewith.

In these drawings, in which like reference numerals indicate like parts:

70 Figure 1 is a fragmentary perspective view illustrating diagrammatically the arrangement of wheel, work, steadyng support and driving mechanism involved in a machine embodying this invention;

75 Figure 2 is a diagrammatic view showing how

a work blank is ground to ultimately conform to the exact curvature of the steadyng shoe;

Figure 3 is a diagrammatic perspective view showing the operative parts of an automatic machine embodying this invention;

Figure 4 shows a front elevation of one particular embodiment of our invention, which is partly broken away to better illustrate the operating mechanism;

Figure 5 shows an end elevation of the work 10 loading device with a work piece supported in the steadyng shoe in grinding position;

Figure 6 is a fragmentary rear elevation showing a work piece supported by the steadyng in 15 grinding position and engaged by the work rotat- ing mechanism;

Figure 7 is a fragmentary end elevation of the work receiving and supporting mechanism in 20 retracted position to receive a fresh work blank prior to a grinding operation;

Figure 8 is a similar fragmentary view showing a work piece being discharged from the steadyng shoe upon completion of the grinding operation;

Figure 9 is a fragmentary sectional view taken 25 approximately along the line 9—9 of Figure 5;

Figure 10 is a sectional view through the control valve taken along the line 10—10 of Figure 4;

Figure 11 is a sectional view through the control valve showing the relative piston and port 30 positions; and

Figure 12 is a sectional view taken along the line 12—12 of Figure 11 showing the throttled exhaust fluid control.

In explanation of the principles underlying our 35 invention, reference is to be had to Figs. 1 and 2 of the accompanying drawings, wherein a work blank "W" is shown as peripherally supported in grinding position substantially throughout its entire length by a steadyng shoe 10 which is 40 provided with a concave arcuate work supporting surface of such curvature that it will exactly mate with the finished cylindrical work surface as shown in Figure 2. Since the work blank W is peripherally supported for rotation within the steadyng shoe 10, it has been found advisable to cut away part of the concave supporting surface, thereby providing two supporting surfaces 12 and 13, having the same axis and forming parts of the same cylindrical surface, to minimize 45 the friction between the work and the steadyng shoe and still provide ample work support for an accurate grinding operation.

The work may be engaged for rotation within 50 said steadyng by any suitable mechanism, 55 which in the present instance comprises two axially slidably, spring supported heads 14 and 15 arranged to simultaneously and frictionally engage the end faces of the work and positively rotate it without offering any support thereto. In 60 other words, the work rotating mechanism must be so arranged that it will positively rotate the work piece W during a grinding operation caused by a rotatably driven grinding wheel 16, which may be moved relatively towards and from the 65 steadyng shoe 10 to grind the work, but the thrust of the grinding wheel must be wholly received by the work supporting shoe irrespective of the type of work rotating device employed. The work and the wheel are preferably rotated 70 in the same direction at the point of contact, as indicated by the arrows in Fig. 2, so that the wheel tends to aid in the work rotation. As shown by the dotted and full circles in Fig. 2, the work at first rides on the outer portions of the shoes,

but gradually approaches the final position of mating with the shoe surfaces when the correct size has been attained. It will be noted that since this work blank prior to grinding does not 5 seat within the accurately finished concave supporting surfaces 12 and 13 but only engages them at two extreme points, any roughness upon the periphery of the work blank prior to grinding would not engage these accurately finished surfaces 10 12 and 13 and create injury thereto.

This new method of grinding has been applied to an automatic grinding machine, one embodiment of which is illustrated diagrammatically in Fig. 3 and in detail in the remaining figures. 15 This machine comprises a base 25 arranged to carry a wheel slide 27 adapted to move transversely on said base on the V-way 29 and flat way 30 thereby causing the grinding wheel 16 rotatably supported on a spindle journaled with 20 in the wheel slide, to approach or recede from the grinding zone. The grinding wheel may be rotated by any suitable means such as shown in the prior United States Patent to Charles H. Norton #1,779,779.

25 Work supporting mechanism

One of the principal features of this invention involves the provision of a work supporting shoe or steadyrest 10 as previously described. To 30 properly support said steadyrest member, a bed 32 is firmly but adjustably secured to the forward portion of the base 25 in front of the grinding wheel by bolts 33 and nuts 34 screwed thereon. The bed 32 is provided with flat ways 36 and dovetailed ways 37 which serve to slidably support a member 39 so that it may be moved towards and from the grinding wheel in a direction parallel to the wheel slide movement. A gib 40 is provided at one side of the dovetailed ways 40 and may be adjustably positioned by screws 42 locked in position by nuts 43 to frictionally engage the slidable member 39 and take up any lost motion between member 39 and its support as it moves within the ways 37. The slidable member 39 is further provided with a flat top surface 45 within which is tapped a threaded hole 46 adapted to receive a cap screw 47 which passes through a support member 48 seated upon flat surface 45 and serves to vertically pivot member 48 on member 39. To angularly locate support member 48 relative to member 39 about the cap screw 47, the support member 48 is provided with a rearwardly extending portion 50 which is clamped between the screws 51 and 52 threaded respectively into two lugs 53 and 54 projecting from the top of member 39 as shown in Fig. 9.

To lock the screws 51 and 52 in fixed adjustment, lock nuts 55 and 56 are provided which are respectively threaded thereon. The support member 48 is provided with an arcuate concave top surface 58 adapted to support a block 60 having an arcuate convex surface shaped to mate with the surface 58. Block 60 is adjustably and angularly secured to member 48 about a horizontal axis by cap screws 64 and set screws 65 whereby the respective convex and concave surfaces may be slid upon each other to angularly position block 60. The forward portion of block 60 is arranged to receive and rigidly support the steadyrest shoe 10 which serves to peripherally support each work piece during its grinding operation as shown in Figs. 1, 2, 3 and 5.

To produce an accurate grinding operation so that the work will be ground to the same diameter 75 throughout its entire length, the axis of each

piece of ground work must necessarily be aligned to lie parallel with the grinding wheel axis. Thus the steadyrest axis may be adjusted to lie within a horizontal plane by adjusting screws 64 and 65 and the steadyrest axis may then be brought parallel with the wheel axis by adjusting screws 51 and 52 and locking them in position by means of lock nuts 55 and 56. Further adjustments may be provided as desired.

10

Work gripping and rotating mechanism

Another important feature of this invention involves the provision of a work gripping and rotating mechanism which serves to yieldingly engage the work and rotate it while it is supported wholly by and moves relative to the arcuate steadyrest supporting faces 12 and 13. This is accomplished by means of a rotatable yielding device capable of following up the rearward movement of the work center as the grinding operation causes a reduction in work size. In the present instance we utilize rotatable gripping members frictionally engageable with each end of the work, and a positively actuated power driven mechanism to retract the gripping members from the work in timed relation with the grinding cycle. In order to make the work gripping and rotating device most effective, it is essential that the work gripping heads, such as the heads 14 and 15 shown in Fig. 1, engage both ends of the work piece "W" close to its periphery so that the torque and the engaging friction may be maintained as high as possible as compared to the rotating effect of the grinding wheel upon the work. It is also essential that the work gripping heads be of a smaller diameter than the finished work piece since in the present machine the grinding wheel 16 is of sufficient width to grind the entire work surface in a single plunge cut grinding operation. If the work were to be gripped near its axis there might be slippage causing an uneven work rotation resulting in flat spots on the work and a consequent imperfect grinding action.

In the preferred construction of our automatic grinding machine, a pair of rotatable, axially slideable work rotating spindles 67 and 68 are journaled within bearings in the front part of the base 25 so that they will always be coaxial with a finished work piece. These spindles are both rotated in synchronism in the opposite direction to the wheel rotation so that the work surface travels in the same direction at the point of grinding, whereby the grinding wheel may assist in driving the work. This spindle rotation is accomplished by pulleys 69 and 70 slidably mounted upon the spindles 67 and 68 and respectively driven by belts 74 and 75 from a pair of pulleys 76 and 77 fixed to a drive shaft 79 gear connected to a main drive shaft, as disclosed in the prior patent to Norton #1,779,779.

The work gripping means may comprise two heads 82 and 83 affixed to the inner end of the spindles 67 and 68 and frictionally engaging the work as shown in Fig. 6 so that there will be no tendency for the work rotating mechanism to center and support the work during its rotation. However, our preferred type of work gripping head is shown in Fig. 1 wherein the heads 14 and 15 are secured to the spindles 67 and 68 by means of springs 85 and 86 respectively which in the present instance have been welded at each end to the spindles and respective work gripping heads. These springs permit the center lines of the work and the driving spindles to be out of

alignment to a slight extent as required by a change in size of the work. This particular construction minimizes any tendency to center and support the work by the rotating means and has, therefore, allowed the work to be wholly supported by the steadyrest shoe 10 during the work rotation and yet to be driven positively as it moves farther into the steadyrest. Whatever the type of work gripping head utilized, it has been found advisable to recess the end of each head which grips the work so that said head may engage the work with an annular face adjacent to the work periphery as illustrated by the surface 88 upon head 15 in Fig. 1. Due to the fact that the ends of the work may be covered with an oil film, it has also been found advisable to knurl the work gripping surfaces.

The axial movement of the spindles to automatically grip the work during the grinding cycle and thereafter releases it in timed relation to receive a fresh work blank is similar to the construction as shown in the prior patent to Norton #1,779,779, wherein the spindles 67 and 68 are moved by levers 90 and 91 pivoted to the machine base by studs 92 and 93 respectively. The upper ends of these levers are provided with yoked portions 95 and 96 connected to engage collars 97 and 98 affixed to the respective spindles 67 and 68, whereby any movement of levers 90 and 91 will cause a corresponding axial spindle movement toward or from the ends of the work. The lever 91 is shaped like a bell crank and is provided with a downwardly extending portion 100 connected by a pivot pin to a connecting rod 101. In order to move the two levers 90 and 91 simultaneously toward or from each other, the lower arm of lever 90 is provided with a single gear tooth projection 103 engaging with the mating projection 104 of a bell crank lever 105 pivoted to the base of the machine by a stud 106. Lever 105 is provided with a depending arm 110 which is pivotally connected to the rod 101. A further and substantially horizontal arm 111 is provided on bell crank lever 105 and serves to 45 pivotally support a depending adjustable weight 112 therefrom. This mechanism as illustrated in Figs. 3 and 4 is so arranged that the pull of weight 112 normally acts to force the work engaging heads towards each other to grip the 50 opposite ends of a work piece W with an equalized pressure during the work rotation.

To automatically separate the work driving heads from the work and release the finished work upon completion of a grinding cycle, and permit 55 a new work piece to be placed in the grinding zone for engagement with the driving heads, an adjustable positively actuated intermittent mechanism is provided to act in timed relation with an automatic wheel feed. This is accomplished in a 60 similar manner as shown in the patent to Norton #1,779,779 wherein a slowly revolving member acting in timed relation to the grinding feed is arranged to strike the lower end of one of the 65 spindle actuating levers and force it and the parts associated therewith to retract the work gripping heads at the proper time in the work grinding cycle.

As illustrated in Figs. 3 and 4, a roller 115 is 70 rotatably mounted upon a stud 116 secured at one end of an adjustable arm 118 rotatably mounted at its opposite end upon a camshaft 119. A projecting arm 120 is fixedly mounted upon the camshaft 119 and is provided at its outer end with an adjustable engaging screw 122, the outer end 75 of which engages arm 118 and causes it to rotate

with shaft 119. It will thus be seen that any adjustment of screw 122 will angularly position arm 118 relative to other operating mechanisms affixed to camshaft 119. The connecting rod 101 is provided with a head 125 at its end adjacent to the camshaft 119, said head being pivoted by means of a stud 126 to the lower end of lever arm 100.

The head 125 carries a depending, adjustable arm 128 pivoted thereto by means of a pin 130 and angularly adjustable by means of an arcuate slot 134, the side faces of which may be securely engaged by a nut 135 threaded upon stud 126 to lock the depending arm 128 in correct angular position. The lower portion of depending arm 15 128 is provided with a surface 137 which, due to the adjustment of arm 128, may be so positioned that it is in the path of roller 115. As the cam-shaft 119 rotates, the adjusting screw 122 forces the roller arm 118 and roller 115 about its axis 20 with shaft 119 and the roller 115 strikes the surface 137 on arm 128 swinging the linkage mechanism toward the left thus moving the yoke portions 95 and 96 outwardly and causing the work gripping heads to simultaneously withdraw from the end faces of the work piece W.

To prevent a rapid dropping of the weight 112 and consequently a too sudden motion of the spindles 67 and 68 in gripping a new work blank after roller 115 has left surface 137, we preferably 30 mount weight 112 so that its lower portion acts as a dash pot system as shown in Fig. 3. The piston or weight 112 is surrounded by a dash pot cylinder 140 which is provided with an opening 35 to the atmosphere controlled by an adjustable air valve 142 so arranged that a controlled leakage of air may serve to cushion as well as retard the downward motion of weight 112. By varying the weight 112 and adjusting air valve 142, the spindles 67 and 68 may be moved slowly or rapidly 40 towards each other to grip the work and rotate it during grinding.

The bottom of the dash pot 140 is provided with a series of perforations or holes 143 to let air rapidly fill the cylinder as piston 112 is lifted so that 45 the work gripping heads may be quickly disengaged from the ends of the work. To prevent any air from escaping through holes 143 during the downward movement of piston 112, a soft 50 leather or rubber disc 145 is placed in the bottom 55 of the dash pot thereby serving to effectively prevent any escapement of air through holes 143 during the downward piston stroke. Thus it will be noted that the work gripping mechanism is arranged to rapidly release the work piece upon completion of grinding, and to engage the work either slowly or rapidly as desired.

Cross feed mechanism

This machine also provides for an automatic 60 cyclic wheel feed mechanism which causes the grinding wheel to feed toward the steadyrest shoe for a predetermined distance and then upon completion of the grinding operation to withdraw therefrom, said feed operating in precise 65 timed relation to the other operative features of the machine. To accomplish this, the grinding wheel is rotatably mounted within a cross slide which has a feed screw connected thereto in the usual manner. The feed screw is automatically 70 rotated by a power operated mechanism and the rate of rotation and direction of movement is accurately regulated by another automatic device preferably a cam, so that the wheel may be fed forward a predetermined extent and then with- 75

drawn to its initial position. The power employed to rotate the cross feed screw in the present instance comprises an adjustable weight arranged to feed the wheel into the work as regulated by 5 the cam, and the rotation of said cam serves to withdraw the wheel and reset the weight for the next infeed of the wheel. The length of the feeding stroke may be varied without changing the cam by connecting said cam with the feed 10 screw by means of a chain passing over a sprocket on the screw shaft and adjustably connecting one end of the chain to a lever which is rocked by the cam.

This cross slide mechanism is preferably patterned similar to the construction shown in the prior patents to Norton Nos. 762,838 and 1,443,924 wherein a half nut 150 is secured to a depending portion upon the under side of the wheel slide 27 which is screw threaded to engage corresponding 20 threads upon a feed screw 152. The feed screw which is rotatably journaled in the base of the machine has a gear 153 secured to its forward end and meshing with a pinion 154 affixed to a shaft 155 rotatably mounted within the base. A 25 hand feed lever 158 is mounted upon the outer end of shaft 155 to rotate therewith and it carries a micrometer adjusting device 159 such as is clearly described in the prior Patent #762,838. This device permits adjustment of the feed arm 30 162 relative to the gear wheel 163 and comprises a pinion 164 meshing with gear 163 and a crank arm 165 adjustably clamped to the extension 166 of a shaft supporting pinion 164. By pulling out a plunger 168 from an opening 169 in the index 35 plate 170 affixed to the arm 162, the crank arm 165 may be revolved the required amount to adjust arm 162 relative to the gear wheel 163. This construction makes it convenient to position the grinding wheel as desired relative to the work as 40 well as to make necessary adjustments to compensate for the wheel wear and it even makes it possible to feed the wheel by hand whenever desired.

45 Cam controlled power drive for feed screw

The feed screw is preferably rotated by a cam controlled mechanism utilizing a cam and a follower operatively connected to the feed screw, and so arranged that the distance and rate of 50 travel of the wheel into and away from the work are dependent upon the contour of the cam. This is best accomplished by mounting a cam 174 upon camshaft 119 in fixed angular relation to arm 120 also fixed on said shaft. To positively 55 rotate the cam 174 at the required rate a worm 176 is mounted upon a shaft 177 journaled within the base and said worm is maintained constantly in mesh with a worm gear 178 mounted upon a shaft 179 (Fig. 4). Shaft 179 also is provided 60 with a gear 181 affixed thereon which in turn meshes with an intermediate gear 182 arranged to drive a gear 183 keyed on the camshaft 119 to rotate arm 120 and cam 174 as shown in Figs. 3 and 4 and also in the Patent to Norton #1,779,779. 65 Power is applied from any suitable source to rotate the shaft 177, such as is shown in said patent, and the power may be engaged or disengaged to operate the machine by means of a clutch 180 controlled by an operating lever 175 on the front 70 of the machine as is shown in Fig. 4.

To translate the motion of the cam 174 so that the wheel feed movement may be accurately regulated, a lever 184 (Figs. 3 and 4) is mounted upon a pivot 185 secured within the base. The short 75 arm 186 of lever 184 is provided with a yoke por-

tion which rotatably supports a roller 188 upon a pin 189 so that the roller may always engage the operative surface of cam 174. To transmit the cam motion from lever 184, a chain 194 is utilized. This chain passes over a sprocket 195 5 affixed to one end of a sleeve 196 which is rotatably mounted upon shaft 155 and has the gear wheel 163 affixed to its end. The lever 184 is provided with an upstanding arm 198 which is so shaped that the upper end of chain 194 may be 10 adjustably secured thereto by a slideable clamping member 199. The lower end of chain 194 is connected by a weight 202, which is slidably mounted within a guard 203 upon the front of the machine. This weight is of sufficient size to turn sprocket 15 195 and the associated mechanism causing a rotation of the feed screw 152 to feed the grinding wheel into the work and always maintain the follower roll 188 in firm contact with the face of cam 174. The cam 174 is so shaped that as 20 it rotates, it will cause the grinding wheel to assume an initial rapid feed toward the work until the wheel is about to contact therewith and thereafter feed the wheel into the work slowly until the work has been reduced approximately 25 to the correct size.

During the final grinding stage the feed mechanism is preferably held immovable for a short period of time by means of an adjustable stop device 204 such as shown in the patent to Norton, 30 #1,779,779 to permit the grinding wheel to complete the grinding operation and spark out. Thereafter a further movement of the cam serves to rapidly remove the wheel from the work during which time the finished work piece may be ejected 35 and a new work blank automatically inserted as will be hereinafter described. It will thus be noted that the weight 202 serves to rotate the feed screw only as limited by the contour of cam 174 40 during the cam rotation to produce an accurate cyclic feed movement of the wheel relative to the work, and the return motion of the wheel from the grinding zone to its initial grinding position is caused by an abrupt rise of the cam 174, which turns the feed screw in the opposite direction. 45

Adjustment of the feeding stroke

Although the feeding motion is necessarily limited by the contour of the cam, the extent of feed per cycle may be varied. To accomplish this, the 50 upper arm 198 of lever 184 is made involute shaped as shown in Figs. 3 and 4. Thus by altering the position of the slideable clamping member 199 along the arm 198 the effective length of lever arm 198 may be changed with a corresponding variation upon the feeding movement of the grinding wheel. Thus the nearer that the clamping member 199 is slid toward the pivot pin 185 along lever arm 198 the less will be the extent for wheel feed and vice versa. To set up the 55 feed mechanism for a particular piece of work would be accomplished identically as described in the Patent #1,779,779.

Magazine feed and work presenting mechanism

Our invention further contemplates an automatic feeding mechanism whereby work blanks may be successively presented within the grinding zone, and then ground and ejected from a grinding position in timed relation to the operation of the wheel feed and work gripping mechanism. To accomplish this, a yoke member 205 is rigidly secured to the bed 32 of the work supporting mechanism by screws 206. The top of member 205 has an adjustable bracket 207 af- 70 75

fixed thereon which in turn supports a magazine 208 adapted to hold a multiplicity of work blanks W and individually feed them into the grinding zone. An anvil member 210 secured to the block 5 60 adjacent to and in the rear of steadyrest shoe 10 is provided with a work supporting face 211 which lies under the mouth of the magazine 208 and prevents work from being fed into the machine during the grinding operation as shown in 10 Figs. 3 and 5.

To feed a single work piece from the magazine 208 into the steadyrest shoe 10 so that it will be peripherally supported thereby during grinding, means are provided which automatically retract 15 the steadyrest shoe from the grinding zone until it lies directly under the mouth of the magazine 208 as shown in Fig. 7. This is easily accomplished by a fluid pressure mechanism, which in the present instance constitutes a pneumatically 20 operated piston and cylinder device operated in cyclic timed relation to the wheel feed by means of a fluid pressure valve actuated by a cam upon the same shaft which carries the wheel feed cam. A cylinder 215 is clamped to the bed 32 and has a piston 216 slidably mounted therein. A piston rod 218 is secured to the piston at one end and to member 39 at the other end as shown in Figs. 3, 5 and 9. Thus it will be seen that any movement of piston 216 within the cylinder 215 will be 30 transmitted through piston rod 218 to move member 39 within its supporting ways 36 and 37, thereby causing the steadyrest shoe 10 to move through a corresponding distance towards or from the grinding zone.

35 A coil spring 220 is mounted upon piston rod 218 within cylinder 215 and under compression between a cylinder head and the piston thereby tending to force the piston 216 towards the rear of the cylinder and the steadyrest shoe away 40 from the grinding zone to a position where it may receive a work piece as shown in Fig. 7. A vent 222 is provided at the forward end of the cylinder 216 so that no air may be trapped within the forward end of the cylinder and thereby hinder the action of the spring tending to move the piston.

The rear cylinder head is provided with a port 224 connected with a port 225 in a control valve 227 by a pipe line 228. It will thus be seen that 50 fluid pressure controlled by the valve 227 and passing into cylinder 215 through port 224 will serve to move piston 216 and compress spring 220 until the piston engages an abutment 230 at which position the steadyrest shoe 10 has moved 55 into the grinding zone as shown in Fig. 5. When the fluid pressure is withdrawn from port 224 the spring 220 serves to move piston 216 to its rearward position which may be adjustably located by means of a stop screw 232 and lock nut 233 in the rear cylinder head (Fig. 5), at which position the piston acting through piston rod 218 and other associated parts has served to withdraw the steadyrest shoe 10 from grinding position to a position directly under the mouth of 65 magazine 208 to receive a fresh work blank prior to a grinding operation as shown in Fig. 7.

The fluid pressure control valve 227 in the present instance pneumatically controls the operation of piston 216 to feed successive work 70 blocks from the magazine to grinding position in timed relation to the cyclic wheel feed and the periodically operated work gripping mechanism. This is accomplished by operating said control valve by a cam 235 affixed to the camshaft 119 75 and acting in precise timed relation to the move-

ment of the feed cam 174 and the arm 120 which act to time the operation of the work gripping and rotating device. The cam 235 is secured to camshaft 119 in proper angular relation to feed cam 174. The valve 227 is secured to the base 5 of the machine in such a position that cam 235 will periodically engage a roller 236 operatively connected with said valve.

The valve 227 is preferably of the familiar balanced piston type wherein two spaced pistons 238 10 and 239 are slidably mounted within a cylinder 240 and connected to a piston rod 242 having the roller 236 rotatably affixed at its lower end by means of a pin 243. A coil spring 245 is mounted upon piston rod 242 under compression against the 15 lower head of cylinder 240 and a member 246 carrying the roller 236, whereby pistons 238 and 239 will be maintained at the lower end of cylinder 240 except when roller 236 is engaged by the high point of cam 235. To adjust the positions of pistons 238 and 239 within the valve cylinder, piston rod 242 has been threaded at its lower end and is screwed into member 246 the desired amount and locked in position by means of lock nut 248 as shown in Fig. 10.

To operate piston 216 and the associated work presenting mechanism, fluid under pressure (in the present instance compressed air, although oil could easily be utilized by providing a supply tank and pump and piping the exhaust fluid 30 back thereto) is passed through pipe 250, check valve 251, pipe 252 and through port 254 into the chamber 255 between pistons 238 and 239. When the pistons are at the lower end of the valve cylinder 240, that is when the roller 236 35 is not acted upon by the high point of cam 235, fluid under pressure is free to pass out of chamber 255 through port 225, pipe 228 and through port 224 into the rear of cylinder 215 to move piston 216 and consequently move the steadyrest into the grinding zone, thereby presenting a work blank in grinding position. Whenever the roller 236 is engaged by the high point of cam 235, the pistons 238 and 239 have been moved to the respective dotted line positions indicated in 45 Figs. 3 and 11 at which position piston 238 has been moved up to cover port 254 and effectively shut off the flow of fluid pressure into cylinder 215. During the time port 254 is closed the spring 220 within the cylinder 215 will act to 50 move the piston 216 toward the rear of the cylinder and the fluid therein will exhaust through port 224, pipe 228, port 225 into chamber 255 and out into the atmosphere through an exhaust port 257 which has been uncovered by the upward movement of piston 239 (Figs. 3, 10 and 12).

To cause piston 216 to move back slowly and withdraw the steadyrest shoe from the grinding zone at a desired rate, a screw 258 may be arranged to adjustably throttle exhaust port 257 60 and thereby cause the rear of cylinder 216 to act as a dash pot and retard the action of spring 220. When screw 258 has been adjusted, it may be conveniently locked in position by means of a lock nut 259. It will, of course, be apparent 65 that port 257 is closed by piston 239 during the flow of fluid pressure toward cylinder 216 and as a consequence only acts in the exhaust circuit.

When the piston 216 is in its rearward position 70 and the steadyrest is receiving a fresh work blank from the magazine as shown in Fig. 7, two spring supported, pivotally mounted arms 262 and 263 serve to catch the work and cushion its fall so that it may not mar the accurate work support- 75

ing surfaces 12 and 13. These arms are pivotally mounted upon the opposite side faces of member 205 so that as a work blank falls from the mouth of the magazine its ends will be caught by two 5 similar recessed arcuate portions in the arms 262 and 263, one of which recesses 265, is shown in arm 262 as illustrated in Figs. 5, 7 and 8. A screw 267 serves to pivotally support arm 262. A lug 270 projects from the side face of member 10 205 adjacent to arm 262 and directly above projecting portion 271 upon the arm 262. A screw 272 is threaded through lug 270 so that it may adjustably engage projection 271 and thereby limit the upward movement of arm 262 about 15 pivot 267. A spring 273 affixed to member 205 at one end and pressing against the underside of arm 262 at its other end, serves to keep the arm in its upward position at which point a work piece falling into the steadyrest would first 20 be engaged by the recessed arcuate portions in arms 262 and 263 and then due to its weight be gently positioned within the steadyrest shoe 10.

During the operation of the machine, the camshaft is slowly and constantly rotating and 25 the action of the cams 174 and 235 and arm 120 are so timed in relation to each other than when the steadyrest is in position to receive a fresh work blank, the wheel is withdrawn from grinding position and the work engaging heads are 30 completely retracted. Figs. 3 and 5 of the drawings show the relative positions of the operating mechanism just as the grinding wheel has completed a grinding operation. Since camshaft 119 is always rotating in a counter-clockwise direction (Fig. 3) the roller 188 is engaged immediately 35 upon completion of the grinding operation by the rise of feed cam 174 causing the lever arm 188 to move in a clockwise direction and lift chain 194 and weight 202. The upward movement of 40 chain 194 rotates sprocket 195 in a clockwise direction and acts through the associated feeding mechanism to move the grinding wheel back away from the grinding zone. At the same time that the rise in cam 174 starts the wheel away 45 from the work, roller 115 strikes the depending lever 128 and causes the spindles 67 and 68 to withdraw the driving heads from engagement 50 with the work. Before the roller 188 has been engaged by the high point on the feed cam 174, roller 236 is engaged by the high point of cam 235 55 moving valve pistons 238 and 239 to their upper position (shown in dotted lines of Figs. 3 and 11) thereby releasing spring 220 within cylinder 215 and causing the finished work piece W and steadyrest 210 to be withdrawn from the grinding zone.

As the steadyrest is withdrawn from the grinding zone, the finished work piece supported thereby is automatically ejected therefrom by the sloping end faces of the work receiving arms 262 and 263 as shown in Fig. 8. Upon being ejected from the steadyrest, the finished work piece is permitted to fall into a chute 275 (Fig. 6) from which it may slide into a bin, not shown. The chute 275 is fixedly supported by a bar 277 passing through the work supporting mechanism and firmly clamped to the yoke member 205 by nuts 278 and 280 screwed upon one end of a threaded portion 281 on bar 277. It will be noted that 65 when the steadyrest member is moved forward into the grinding zone, the chute 275 is received within the recess 283 within the block 60 which is moved by piston 216 and its associated parts. Thus, the chute 275 always remains in a fixed 70 position.

After the finished work piece has been ejected, the rearward movement of the steadyrest continues until the piston 216 engages stop screw 232 and the empty steadyrest lies directly below the magazine mouth as shown in Fig. 7. At this 5 time a work blank falls from the magazine into the steadyrest and is broken in its fall by first being caught by the recessed portions within the arms 262 and 263, one of said recessed portions being indicated by the dotted line 265 in Figs. 10 10, 5, 7 and 8. The operation of the machine is so timed that the roller 236 now passes to the low point of cam 235 causing pistons 238 and 239 within the valve 227 to close the exhaust port 257 (Fig. 11) and again enter fluid under pressure 15 into cylinder 215 moving piston 216 forward against the tension of spring 220 and thereby moving the fresh work blank into grinding position. Due to the fact that the work receiving arms 262 and 263 are spring supported, the 20 forward movement of the work blank within the steadyrest will permit the arms to spring out of the way. The anvil 210 also moves forward at this time since it is supported by the block 60, and presents its top face 211 under the next work 25 blank within the magazine thereby permitting only one work piece to feed into the steadyrest per grinding cycle.

The escape valve 142 controlling the exhaust of air from the dash pot cylinder 140 has been 30 so regulated that the weight 112 may lower as soon as a new work blank is presented in grinding position thereby causing the spindles 67 and 68 to move axially toward the work, grip it and rotate it until completion of the grinding operation. As soon as the work has been automatically presented in grinding position, the high point 35 of cam 174 passes roller 188 thereby causing the wheel to rapidly approach the work supported by the steadyrest and go through another automatic grinding cycle. It will be seen that the operation of this machine is entirely automatic and it is only necessary to maintain duplicate work blanks within the magazine.

Having thus described our invention, what we 45 claim as new and desire to secure by Letters Patent is:

1. A grinding machine for round work comprising a rotatable grinding wheel, a work support having a work supporting surface peripherally engageable and shaped to mate with the ground surface of the finished work piece which is arranged to constitute the sole support and hold the work in correct grinding relation with the wheel, means to cause relative feeding movement between the wheel and the work support to grind the work and non-supporting means independent of the work support to cause the work to rotate at a controlled rate in the same direction as the wheel at the point of contact. 50

2. A grinding machine for round work comprising a rotatable grinding wheel, a work support having a surface engageable with and shaped to support the peripheral surface of the work piece being ground and arranged to serve as the 55 sole support to hold the work in grinding relation with the wheel, means to cause a relative feeding movement between the wheel and the work support to grind the work and a work driving mechanism including a universal driving connection engaging the ends of the work which causes the work to rotate at a controlled rate 60 irrespective of any radial movement of the work as it reduces in size. 65

3. A grinding machine comprising a base, a

- wheel slide having a grinding wheel rotatably mounted thereon, a work holder arranged to support a cylindrical work piece upon its peripheral surface, means independent of the work holder to flexibly engage both ends of the work simultaneously and transmit rotation thereto, and means to cause the grinding wheel to approach the work to perform a grinding operation.
10. 4. A grinding machine comprising a rotatable grinding wheel, means to rotate the wheel, a work holder arranged to peripherally engage a cylindrical work piece substantially throughout the entire length of the portion being ground and serve as the sole support therefor, means independent of the work support to grip the work piece and rotate it in the same direction as the wheel rotation at the point of contact while supported and positioned in the grinding zone solely by the work holder, and means to cause a relative feeding movement between the grinding wheel and the work holder to grind the work.
5. A grinding machine comprising a rotatable grinding wheel, means to rotate the wheel, a work holder arranged to peripherally support a cylindrical work piece substantially throughout its entire length, means independent of the work holder including two driving members which engage the ends of the work piece, means to simultaneously and synchronously rotate said work engaging members to rotate the work while supported by the work holder and means to cause a relative approach between the grinding wheel and the work holder to grind the work.
30. 6. A grinding machine for round work comprising a rotatable grinding wheel, a work support peripherally engageable with the ground surface of the finished work piece which is arranged to hold the work in grinding relation with the wheel, means to cause a relative feeding movement between the wheel and the work support towards and from each other through a predetermined grinding cycle to grind a work piece to a given size and means independent of the work support to non-supportably rotate the work at a controlled rate while it is maintained in grinding position solely by said work support.
7. A grinding machine for round work comprising a rotatable grinding wheel, a work support peripherally engageable and shaped to mate with the ground surface of the finished work piece which is arranged to hold the work in grinding relation with the wheel, a cam controlled mechanism arranged to feed the wheel and the work support relatively towards each other to grind a work piece to a predetermined size and means independent of the work support to cause the work to rotate at a controlled rate during the grinding operation.
60. 8. A grinding machine for round work comprising a rotatable grinding wheel, a work support having a work supporting surface peripherally engageable and shaped to mate with the ground surface of the finished work piece which is arranged to hold the work in grinding relation with the wheel, means to cause relative feeding movement between the wheel and the work support in a predetermined cycle to grind work pieces successively, means independent of the work support to cause the work to rotate at a controlled rate during the grinding operation and mechanism for automatically feeding work pieces successively to the grinding zone in timed relation with the wheel feeding cycle.
70. 9. A grinding machine comprising a rotatable grinding wheel, a work steadyng member arranged to peripherally support the work in the grinding zone, mechanism to relatively move the grinding wheel and steadyng member toward and from each other for a predetermined grinding cycle, means independent of the work steadyng member to rotate the work while wholly supported by said steadyng member, and mechanism arranged to discharge a finished work piece from the steadyng member upon completion of the grinding cycle.
10. A grinding machine for cylindrical work comprising a rotatable grinding wheel, a work support peripherally engageable and shaped to mate with the ground surface of the finished work piece which is arranged to hold the work in grinding relation with the wheel, means to cause relative feeding movement between the wheel and the work support in a predetermined cycle to grind work pieces successively, means independent of the work support to cause the work to rotate at a controlled rate in the same direction as the wheel at the point of contact, mechanism for automatically feeding work pieces successively to the grinding zone in timed relation with the grinding cycle and means for automatically discharging work pieces from the grinding zone upon completion of the grinding operation and in timed relation with the wheel feed cycle.
11. A grinding machine comprising a rotatable grinding wheel, means including a work steadyng member to support the peripheral surface of the work during a grinding cycle, separate means engageable with the work for rotating it while supported within the work holder, means for feeding the grinding wheel and work relatively toward each other during the grinding operation, mechanism arranged to discharge the finished work piece upon completion of the grinding cycle, and means for automatically and successively presenting work blanks to the steadyng member in proper timed relation to the grinding cycle.
12. A grinding machine comprising a rotatable grinding wheel, means to rotate said wheel, a work supporting shoe arranged to peripherally support the work substantially throughout its entire length, means to move the work holder towards and from the grinding wheel to present the work piece within the grinding zone, means to rotate the work within said shoe and means to feed the grinding wheel into the work during the work rotation to cause a grinding operation.
13. A grinding machine comprising a rotatable grinding wheel, means to rotate it, a work holder arranged to peripherally support a cylindrical work piece, means providing a relative movement between the work holder and grinding wheel to present the work in correct grinding relation to the wheel, two driving heads adapted to engage the ends of the work piece and rotate it at a controlled rate and means to simultaneously rotate said heads, thereby transmitting a rotary motion to the work piece during a grinding operation and means to feed the grinding wheel into the work during the work rotation to cause a grinding operation.
14. A grinding machine for round work comprising a rotatable grinding wheel, a work support having an extensive surface peripherally engageable and shaped to mate with the ground surface of the finished work piece which is arranged to hold the work in grinding relation with the wheel, means to cause a relative feeding movement between the wheel and the work support in a predetermined cycle to grind work pieces.

successively, means including a work gripping device engageable with the work to cause the work to rotate at a controlled rate in the same direction as the wheel rotation at point of contact, mechanism for automatically feeding work pieces successively into the grinding zone in timed relation with the operation of the work gripping mechanism and the operation of the grinding cycle and means for automatically discharging finished work pieces from the grinding zone upon completion of the grinding operation.

15. A grinding machine comprising a rotatable grinding wheel, means to rotate said wheel, a work holder arranged to support a cylindrical

15 work piece upon its peripheral surfaces, means providing a relative movement between the work holder and the grinding wheel whereby the work may be maintained within the grinding zone, means independent of the work holder to engage 20 both ends of the work piece and transmit rotation thereto, means to eject the work piece from the grinding zone upon completion of a grinding operation, and mechanism arranged to automatically and successively present a new work blank 25 to the work holder after a previously ground work piece has been discharged therefrom.

16. A machine for grinding a work piece having a cylindrical surface, comprising a rotatable grinding wheel, a single work support opposed 30 to the grinding wheel which has an extensive hollow surface shaped and arranged to contact with the cylindrical surface of the work and serve as the sole work support during the grinding operation, a non-traversing support for holding the 35 wheel immovable axially, means to rotate the wheel in a direction towards the work support at the line of grinding contact and thereby tending to hold the work within its support, means to cause a relative feeding movement between 40 the wheel and the work support, and a positively rotated work driving device which engages the work at a point remote from the surface contacting with the work support and serves, without centering or supporting the work, to rotate the 45 latter in the same direction as that of the wheel at the line of grinding contact and at a controlled rate.

17. A machine for grinding a work piece having a cylindrical surface comprising a rotatable 50 grinding wheel, a single work support opposed to the wheel which is engageable with and shaped to support said cylindrical surface and serve as the sole support to hold the work in correct grinding relation with the wheel, means to feed the 55 wheel and the work relatively towards each other and cause the work to be ground, and opposed driving means which frictionally grip the opposite ends of the work and serve to rotate the work during the grinding operation without supporting or centering the same.

60 18. A grinding machine for grinding a round work surface comprising a rotatable grinding wheel, a support engageable with said work surface and shaped to serve as the sole work support during the grinding operation, means to cause a relative in-feeding movement between the wheel and the work support to grind the work, a pair of work rotating members which are relatively movable into engagement with the opposite ends 65 of the work, and means tending to hold said members in frictional and yielding engagement with the work ends, whereby the latter is rotated within its support by the end pressure of said members.

70 19. A machine for grinding a round work sur-

face comprising a rotatable grinding wheel, a work support having a surface engageable with and shaped to support the surface of the work and serve as the sole support to hold the work in correct grinding relation with the wheel, means to feed the wheel and the work relatively and cause the work to be ground, and work driving mechanism, including work gripping members frictionally engaging the opposite ends of the work, a positively rotated driving shaft and a flexible connection between said shaft and a gripping member, which serves to rotate the work within its support without supporting or centering the same.

15 20. A grinding machine comprising a rotatable grinding wheel, a work support having an extensive surface peripherally engageable and shaped to mate with the ground surface of the finished work piece which is arranged to hold the work in grinding relation with the wheel, 20 means to cause a relative feeding movement between the wheel and work support in a predetermined cycle to grind work pieces successively, means including a work gripping device engageable with the work to cause it to rotate at 25 a controlled rate, and means to automatically move the work support into an operative position for grinding and to an inoperative position after grinding to facilitate insertion of work pieces.

30 21. A grinding machine comprising a rotatable grinding wheel, a work support having an extensive surface peripherally engageable and shaped to mate with the ground surface of the finished work piece which is arranged to hold the work in grinding relation with the wheel, means to cause a relative feeding movement between the wheel and work support in a predetermined cycle to grind work pieces successively, means including a work gripping device engageable with the work to cause it to rotate at a controlled rate, 40 and means including a fluid pressure piston and cylinder to automatically move the work support into an operative position for a grinding operation and into an inoperative position after grinding to facilitate insertion of work pieces.

45 22. A grinding machine for cylindrical work comprising a rotatable grinding wheel, a work support having an extensive surface peripherally engageable and shaped to mate with the ground surface of the finished work piece which is arranged to hold the work in grinding relation with the wheel, means to cause a relative feeding movement between the wheel and work support in a predetermined cycle to grind work pieces 50 successively, means including a work gripping device engageable with the work to cause the work to rotate at a controlled rate, means to move said work support into an operative or inoperative position, means to eject a ground work piece from said support when the work support is 55 moved toward an inoperative position after a grinding operation, and a work piece hopper arranged to automatically feed work pieces successively to said work support when it is withdrawn to an inoperative position.

60 23. A grinding machine comprising a rotatable grinding wheel, a work support having an extensive surface peripherally engageable and shaped to mate with the ground surface of the finished work piece which is arranged to hold the work in 70 grinding relation with the wheel, means to feed the grinding wheel toward and from the work support in a predetermined cycle to grind work pieces successively, means including a work gripping device engageable with the work to cause 75

- the work to rotate at a controlled rate, means including a fluid pressure piston and cylinder to move said work support into or out of an operative position, means including a control valve actuated by and in timed relation with the cyclic movement of the wheel to control the admission of fluid to said cylinder to move the work support to and from an operating position, means to eject a finish ground work piece from said work support when the work support is moved to an inoperative position, and a work piece hopper arranged to successively feed work pieces onto said work support when it is withdrawn to an inoperative position.
- 5 24. A grinding machine for cylindrical work comprising a rotatable grinding wheel, a work support having an extensive surface peripherally engageable and shaped to mate with the ground surface of the finished work piece which is arranged to support the work in grinding relation with the wheel, means including a work gripping device engageable with the work to cause it to
- 10
- 15
- 20

rotate at a controlled rate, means to cause a feeding movement of the grinding wheel in a predetermined cycle to grind work pieces successively, means including a fluid pressure piston and cylinder to move said work support into an operative position, means actuated in timed relation with the cyclic wheel feeding movement to admit fluid under pressure to said cylinder to cause the work support to be moved into an operative position, means including opposed work driving spindles engageable with the end of the work in timed relation with the cyclic control mechanism to grip and rotate the work piece, means to return said piston and move said work support to an inoperative position after a grinding operation has been completed, means to eject the finished work piece during said withdrawal, and a hopper arranged to successively feed work pieces onto said work support when it is withdrawn to an inoperative position.
